(57) **CLAIM**

The ornamental design for a fenestrated tip for a spike tap of an irrigation fitting, as shown and described.

DESCRIPTION

FIG. 1 is a perspective view of a fenestrated tip for a spike tap of an irrigation fitting in accordance with our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof shown in a position of use.

The unevenly dashed lines in the drawings are for purposes of illustrating claim boundary that forms no part of the claimed design. The evenly dashed lines in the drawings depict environmental subject matter that forms no part of the claimed design.

1 Claim, 7 Drawing Sheets
